UNITED STATES PATENT OFFICE.

FRANK A. GOODFELLOW, OF ALTOONA, PENNSYLVANIA.

EXHAUST-NOZZLE.

1,122,733.

Specification of Letters Patent. Patented Dec. 29, 1914.

Application filed September 6, 1913. Serial No. 788,494.

To all whom it may concern:

Be it known that I, FRANK A. GOODFELLOW, a citizen of the United States, residing at Altoona, in the county of Blair and State 5 of Pennsylvania, have invented certain new and useful Improvements in Exhaust-Nozzles, of which the following is a specification.

The invention relates to exhaust nozzles for locomotives and has for its primary objects; the provision of a nozzle adapted to break up the body of steam somewhat and secure a better entrainment of the gases in the smokebox but without decreasing the velocity of the body of steam; the provision 15 of a nozzle which will reduce the back pressure in the cylinders; the provision of a nozzle whereby the draft and consequently the capacity of the boiler is increased, and the provision of a nozzle which can be 20 cheaply constructed with a minimum amount of machine work. One embodiment of the invention is shown in preferred form in the accompanying drawings, wherein—

Fig. 1 is a plan view of my improved nozzle, Fig. 2 is a section on the line II—II of Fig. 1, Fig. 3 is a side elevation of a portion of the end of the locomotive, and showing the relative arrangement of the nozzle, petticoat pipe, and stack, and Figs. 4 and 5 are 30 diagrammatic sectional views taken on the lines IV—IV and V—V of Fig. 3.

The nozzle as illustrated in Figs. 1 and 2 is provided with the usual circumferential blower passage 1 communicating with the 35 vertical passages 2 in the upright conical members 3. This arrangement of blower passages is old in the art, and no novelty is claimed therefor. Any other type of blower arrangement might be used without affecting 40 my invention in any way, such invention relating to the shape of the exhaust passage for the steam.

The lower interior portion of the nozzle marked 4 and lying below the line 5 (Fig. 2) 45 is slightly tapered as is common in nozzles, while the portion 6 lying above the line 5 is straight. Projecting inwardly from the surface 6 constituting the periphery of the upper portion of the passage, are the four 50 lugs 7—7—7—7, such lugs being preferably all the same in shape and size. The lower sides of these lugs are formed by inclined planes 8 and 9 (Fig. 2) so that the lugs are in vertical cross section substantially triangular. The converging surfaces 8 and 9

meet on the line 10 which constitutes what may be termed the peak of the lug. This line 10 is inclined upwardly, as clearly indicated in Fig. 2. In the construction as I have used it the dimensions A, B, C, D, and 60 E are as follows:

A—6 $\frac{3}{4}$ inches
B—1 inch
C— $\frac{5}{8}$ inch
D—1 $\frac{1}{2}$ inches
E—2 $\frac{1}{8}$ inches.

The results as hereinafter set forth were secured with a nozzle of the proportions above indicated, and these proportions are 70 the best of which I am aware at the present time. It will be understood, however, that, I do not regard my invention as limited to the foregoing proportions. It will also be understood that I do not regard my invention as limited to the number of lugs as shown, nor to the precise arrangement and shape shown, although this is the preferred arrangement, and the best one of which I have knowledge.

It will be seen that aside from the use of the lugs 7 the nozzle as above illustrated and described is the same throughout as the ordinary type of circular nozzle as almost universally used. The intended function of 85 the lugs 7, and the one which I have found them to accomplish, is the breaking up or deforming of the body of steam as it issues from the nozzles, to a slight extent, but without reducing its velocity. This breaking up of the body of steam serves to secure a better entrainment of the gases in the smokebox, and when the mixture of steam and gases of combustion emerges from the 90 stack they much more completely fill the 95 stack than is the case where a round or circular nozzle of the old type is employed.

The general arrangement of the parts and the cross sectional form of the body of steam and gas are illustrated in Figs. 3, 4, and 5, 100 where F indicates the nozzle, G indicates the petticoat pipe, and H the stack. At a point just above the nozzle the cross sectional area of the body of steam is as indicated in Fig. 5, such cross sectional area being somewhat similar to that of a Maltese cross. The lugs 7 cause the depressions 11, so that the central portion 12 is somewhat condensed. The entraining area of the 105 body of steam is thus materially increased, 110

since the line 13 constituting the periphery of the body of steam in the cross section is considerably greater than the circumference of the body of steam where a round nozzle 5 is used. The openings or recesses 11 are relatively larger than might be expected from the small size of the lugs 7, and this is due, it is believed, to the inclined surfaces 8 and 9 which form eddies or lateral cur- 10 rents away from the center lines of the lugs and extending diagonally at the surface of the stream of upflowing steam. The feature of providing the inclined surfaces 8 and 9 and the inclined peak 10 I regard as of very 15 considerable importance, since this arrangement not only tends to increase the size of the recesses 11, but also prevents the lugs from materially reducing the velocity of the passing body of steam. As a result of this 20 arrangement a much better entrainment of the gases of combustion is secured without an appreciable decrease in velocity, so that a much greater quantity of gas is pulled from the smoke box in a unit of time than 25 is the case where a round nozzle is employed. The lugs are separated by relatively wide spaces so that the lateral currents produced thereby in the stream of fluid issuing from the nozzle do not materially interfere with 30 each other. Otherwise, and with the lugs closely adjacent, the surface of the stream is unduly agitated and broken up, thus increasing the resistance to the forward movement of the stream, reducing its velocity 35 and producing increased back pressure in the engine cylinders.

I have also found that the deformation of the body of steam by the lugs secures another important result tending to improve 40 the draft. This result is the causing of the body of steam to spread out and completely fill the stack before its issuance therefrom, as indicated diagrammatically in Fig. 4. In other words, between the points 5—5 45 and 4—4 the steam spreads out and fills the stack more completely than is the case where an ordinary round nozzle is employed. With the ordinary round nozzle I have found that there is always one portion of 50 the stack which is not filled by the body of steam and in which there is practically no upward pressure, the point not filled ordinarily being the rear portion of the stack. I have found by means of gages placed at 55 the top of the stack that the point of maximum pressure due to the upward velocity of the steam is at the center 14 of the stack, and that such pressure gradually decreases as the edge of the stack is approached. 60 With my improved nozzle I have found that the pressure is not only higher at the central portion 14 than is the case with a round nozzle of corresponding area and working under the same conditions, but also that 65 higher pressure is maintained throughout

the cross sectional area of the stack, the upward pressure as indicated by gages being greater throughout the entire cross sectional area of the stack where my nozzle is employed, than is the case where a round nozzle is employed. With a greater upward velocity through the stack, the inference would be that a greater draft is produced in the smoke box, and this I have found to be the case, as a result of a large number 70 of tests with both types of nozzles. 75

In comparing the results secured by my nozzle with the ordinary round nozzle I have employed a round nozzle of precisely the construction shown in Figs. 1 and 2, but 80 with the exception that the lugs 7 are omitted and the diameter A reduced by a quarter of an inch, so that the diameter of such round nozzle was $6\frac{1}{2}$ inches instead $6\frac{3}{4}$ inches, the cross sectional area of the outlets of the 85 two nozzles thus being made substantially identical. With my nozzle I found as a result of repeated tests that the boiler limit upon a certain locomotive was increased 27 $\frac{7}{10}$ per cent. over the best performance at 90 attainable with the circular nozzle as above described. At equal evaporation I found the back pressure with my nozzle to be 11 per cent. less than with the said circular nozzle, and the ratio of the draft as indicated 95 by manometers connected to the smoke box in the ratio of 16 to 9 in favor of the nozzle with the projections as indicated in Figs. 1 and 2 as opposed to the round nozzle having equal area, but without the lugs. The foregoing is a fair statement of the relative performance of the two nozzles under similar conditions, upon a number of tests. It will be noted that the horizontal obstructing area of the lugs 7 is relatively slight as compared 105 with the cross sectional area of the exhaust passage, the combined horizontal area of the lugs being $2\frac{1}{2}$ square inches as compared with a fraction over 33 square inches in cross sectional area of the nozzle. The utility of the lugs is not limited to use with a nozzle of exactly circular cross section, and it will 110 be understood that the term circular is used in its generic sense to cover a deformed circular shape as well as a true or exact circular shape. I have found that the nozzle may be cheaply constructed, as it can be cast in the form illustrated, and used with practically no machine work, it not being necessary to bore out the interior where a smooth 115 casting is secured. 120

What I claim is:

1. In combination, a locomotive exhaust pipe, a nozzle therefor having its passage communicating therewith and substantially circular in cross section at its outlet with a plurality of lugs projecting from the periphery of the passage toward the center thereof and spaced apart distances such that the lateral currents produced by such lugs 125 130

in the stream of fluid issuing from the nozzle do not materially interfere with each other.

2. In combination, a locomotive exhaust pipe, a nozzle therefor having its passage communicating therewith and substantially circular in cross section at its outlet, with a plurality of lugs projecting from the periphery of the passage toward the center thereof and spaced apart distances such that the lateral currents produced by such lugs in the stream of fluid issuing from the nozzle do not materially interfere with each other, the spacing of the said lugs around the periphery being substantially uniform.

3. In combination, a locomotive exhaust pipe, a nozzle therefor having its passage communicating therewith and substantially

circular in cross section at its outlet with a plurality of lugs projecting from the periphery of the passage toward the center thereof and spaced apart distances such that the lateral currents produced by such lugs in the stream of fluid issuing from the nozzle do not materially interfere with each other, the combined obstructing area of the lugs in a horizontal plane being less than ten per cent. of the cross sectional area of the passage.

In testimony whereof I have hereunto signed my name in the presence of the two subscribed witnesses.

FRANK A. GOODFELLOW.
